UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,644, dated February 16, 1897.

Application filed January 13, 1897. Serial No. 619,127. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for globes or shades for lamps, gas, or electric lights, and has for its object the provision of a novel and artistic harmonious configuration; and it consists in the design hereinafter described, and shown in the accompanying drawings, wherein—

Figure 1 is a plan view of a globe or shade made according to my design, and Figs. 2 and 3 are side views of the same.

The shape of the globe is substantially that of the frustum of a paraboloid merging at its narrowest point into an outwardly-flaring flange that forms the neck of the globe. The upper edge of the globe is formed narrow 25 with beveled-edge scallops, and the surface may be etched or otherwise provided with suitable surface ornamentation.

Having described my invention, I claim—

The design for a globe or shade herein described and shown. 30

In testimony whereof I have affixed my signature in presence of two witnesses.

EDWD. F. CALDWELL.
